(57) **CLAIM**

The ornamental design for an electrical connector thereof, as shown and described.

DESCRIPTION

FIG. 1 is a front, top and right side perspective view of an electrical connector showing our new design;

FIG. 2 is a front elevational view thereof;

FIG. 3 is left side elevational view thereof;

FIG. 4 is a right side elevational view thereof;

FIG. 5 is a top plan view thereof;

FIG. 6 is a bottom plan view thereof; and,

FIG. 7 is a cross-sectional view thereof along line 7-7 of FIG. 6.

The Dash-Dash broken line portion of the figure drawings is included to show portions of the article that form no part of the claimed design. The Dash-Dot broken line portion of the
